UNITED STATES PATENT OFFICE.

RICHARD DOOLEY, OF MERIDEN, CONNECTICUT.

FILE HOLDER.

Application filed November 16, 1921. Serial No. 515,477.

To all whom it may concern:

Be it known that I, RICHARD DOOLEY, a citizen of the United States, residing at Meriden, in the county of New Haven and 5 State of Connecticut, have invented a new and useful Improvement in File Holders; and I do hereby declare the following, when taken in connection with the accompanying drawings and the characters of reference 10 marked thereon, to be a full, clear, and exact description of the same, and which said drawings constitute part of this application, and represent, in—

Fig. 1 a face view of a combined saw set 15 and file holder constructed in accordance with my invention, the file being shown in broken lines.

Fig. 2 a vertical sectional view of the same.

20 Fig. 3 a top view of the same.

Fig. 4 an underside view of the same.

This invention relates to improvement in combined saw sets and file holders, the object being to provide in a single structure a 25 device with which the teeth may be aligned, and filed, and the invention consists in the combination and arrangement of parts as hereinafter described and particularly recited in the claims.

30 In carrying out my invention, I employ a cast-metal handle member 5, formed in its inner end with a transverse slot 6, intersecting at its inner end a triangular opening

7 through which a three-cornered file 8 may 35 be passed. The handle is formed with a longitudinal bore 9 tapered at its inner end to form a butt chamber 10. In this bore is located a wooden plug 11 formed with a slot 12 narrower than the slot 6 in the handle

40 and intersecting an opening 13 corresponding to the opening 7. The plug forms bushing-blocks between which the blade of a saw may be passed to engage with the face of the file 8, so that the edge of the

45 saw may be straightened. Mounted in one side of the handle is a steel anvil 14 which projects through a clearance hole 15, in the plug 11, and is seated in the opposite side of the handle, which is there provided with

50 a stud 16, by which the device may be held in a vise or inserted into a hole formed for it in a workbench or other supporting device. Secured to the handle is a spring-set

17, the head 18 of which stands in line with the anvil 14. Below the anvil 14 is a gage- 55 plate 19, against which the edge of the saw may rest when the teeth are being set. The outer end of the bore is straight and forms a shoulder 20 at the bottom of a recess 21 to receive chuck-jaws 22 and 23, between 60 which the file 8 may be placed and clamped by a set-screw 24. One of the jaws is formed at its inner end with a disk 25 adapted to seat upon the shoulder 20, and above its seat with a notch 26 to receive lugs 27 65 at the lower end of the other jaw, so that they cannot be removed through the outer end of the handle. The set-screw 24 also holds a file-guide 28 provided with a segmental row of perforations 29 for engagement with a pin 30 by which the file-guide is held in its various positions of adjustment. In assembling, the jaws are first introduced through the butt end of the handle, then the plug is inserted to hold the jaws in 75 place and form a bushing for the slot 6 and the plug is held in place by the anvil 14. In use, a file 8 is first inserted into the opening 7 and the edge of the saw straightened. When the teeth are set the file is re- 30 moved and inserted between the chuck-jaws 22 and 23 and gripped therein by the screw 24, the file-guide 28 is turned to the desired angle at which the teeth are to be filed and this guides the eye of the operator in filing 85 the teeth.

I thus combine, in a very simple manner, and in a single device, means for straightening, setting and filing saw-teeth.

I claim:

1. In a file holder, the combination with a handle-member formed with a longitudinal bore tapered at its inner end, of a plug closing the inner end of the bore, said handle and plug formed with a transverse file-opening and with a slot entering the inner end and intersecting the said file-opening, and an anvil mounted in said handle and plug, whereby said plug is interlocked with said handle. 90

2. In a file holder, the combination with a handle-member formed with a longitudinal bore tapered at its inner end and straight at its outer end, of jaws mounted in the outer end of the bore, a plug closing 95 the inner end of the bore and forming a 105

bearing for the inner ends of the said jaws, said handle and plug formed with a transverse file-opening and with a slot entering the inner end and intersecting said file-opening, and an anvil mounted in said handle and plug, whereby said plug is interlocked with said handle.

In testimony whereof, I have signed this specification in the presence of two subscribing witnesses.

RICHARD DOOLEY.
